ELECTRIC CORD REELING MECHANISM

Carl F. Duerr, Jr., Gates Mills, Ohio

Application January 28, 1946, Serial No. 643,855

6 Claims. (Cl. 242—107)

1

This invention relates to mechanisms for winding up and paying out electric conductors.

It is an old art to provide a winding drum or reel and a spring to turn it in the direction to wind up an electric conductor thereon and yieldable to permit it to be turned in the other direction to unwind the conductor by pulling on the conductor, thereby providing an extensible conductor of variable length; the conductor at the reel end being connected to a source of current and at the other end to a lamp or other device to be energized.

In such prior mechanisms the reel or drum rotates; and sliding electric contacts must be provided at the reel to conduct the current into the conductor, with attendant cost for parts, insulation, increased wear and deterioration, and liability of break down and repairs.

It is an object of this invention to provide a mechanism of this class in which the drum or reel itself remains stationary whereby sliding contacts are eliminated, the conductor continuing uninterruptedly from the source to the energized device.

It is another object of this invention to provide for stopping the winding up of the conductor without the necessity of mechanical latches, locks or the like.

Another object is to provide, in a mechanism of this class, means to stop winding up of the conductor at any time comprising means to grip the conductor itself operable by suitable manipulation of the extended conductor.

Another object is to provide a mechanism of this class having a lamp for the device to be energized, and constructed suitably to be installed in the top of a motor car with the lamp in position to function as the "dome light" of the car; and with a conductor or electric cord connected to the lamp which may be unwound or extended by grasping the lamp and pulling upon the cord to convert the lamp into an extension-cord-lamp for use at any point of the car.

Other objects will be apparent to those skilled in the art to which the invention appertains.

The invention is fully disclosed in the following description taken in connection with the accompanying drawing, in which:

Fig. 1 is a sectional view of an embodiment of the invention;

Fig. 2 is a view approximately along the plane 2—2 of Fig. 1, with a rotary winding arm thereof rotated clockwise to a different position; and with some of the parts behind the section plane omitted;

2

Fig. 3 is a side elevational view of the winding arm which is shown in longitudinal section in Fig. 1;

Fig. 4 is a view of the winding arm as shown in Fig. 1 but with a part thereof in a different operative position.

The embodiment of the complete invention comprises an electric cord connected or adapted to be connected at one end to a source of current, and connected or adapted to be connected at its other end to a device to be energized for example an electric lamp, and a mechanism by which the intermediate part of the cord may be wound upon or unwound from a reel, whereby the part of the cord connected to the device to be energized is rendered an extension-cord the length of which may be conveniently adjusted; the reel mechanism and its associated parts are mounted upon a frame, or enclosed within a housing, and the frame may be mounted or disposed in various environments whereby the lamp or device to be energized may be applied to various uses. For example the mechanism may be mounted in the wall of a room of a dwelling, farm building, etc., and the extensible cord led to a floor lamp, fan, inspection lamp, or the like.

The particular housing and arrangement of parts herein illustrated and to be described, has been designed to particularly adapt the housing or frame to be mounted in the overhead interior panel or roof of a motor car; and the device to be energized is an electric lamp; and when the extension cord has been fully retracted and wound upon the reel, the lamp may ordinarily function as a "dome light" within the car; and when the cord is extended or drawn out of the housing by unwinding it from the reel, the lamp on the end of the cord thus extended may be used to illuminate any part of the car, inside or outside for any purpose.

In the drawing therefore I have shown at 1 a main base formed from sheet metal and in the form of a shallow downwardly open pan, having a peripheral flange 2 thereon. Under the pan is a downwardly convex preferably conical cover plate 3 secured to the pan by rivets 4—4 projected through aligned perforations in the flange 2 and in the cover plate. The cover plate and pan therefore provide an enclosing housing for parts therewithin, and the housing may be identified in general by the reference character 5. The housing may be mounted to support it by screws or the like projected through a plurality of perforations 6—6 in the flange 2 and the underlying peripheral portions of the cover plate.

A sheet metal piece preferably circular shown generally at 7 is riveted as at 8-8 to the inner side of the pan bottom indicated at 9, and at its center has a cup form depression 10 formed therein provided with a central perforation 11 whereby a flange 12 is provided. The pan bottom 9 is provided with a central perforation 13 the periphery of which overlaps the interior of the cup form depression 10 in the nature of a flange. A ball bearing has its outer raceway 14 telescoped into the cup form depression 10 with its axially opposite ends abutting the flanges 11 and 13 prior to heading the rivets 8 whereby the ball bearing is trapped in the cup form depression.

A bolt 15 having a conical head 16 is provided and the shank 17 of the bolt is projected upwardly first through a perforation 18 in a sheet metal arm 19 to be described, and then through a washer 20 upon which the inner raceway 21 of the ball bearing abuts at one axial end, and a nut 22 is screwed onto the upper end of the bolt against the upper end of the inner raceway whereby the bolt 17, washer 20, inner raceway 21, and nut 22 are all clamped together by the nut into a rigid assembly, whereby the arm 19 to be described and the bolt 17 and its conical head 16 may all rotate freely on the ball bearing.

At its peripheral portion, the circular piece 7 as at 23 is bent inwardly away from the pan bottom 9 into a preferably frusto-conical form flange providing as at 24 a reel groove between the flange 23 and the pan bottom constituting a stationary reel upon which the cord as will be described is wound.

The said arm 19 which functions as a winding arm is made of sheet metal and generally of channel form comprising a channel web 25 in which the aforesaid perforation 18 is provided; and comprises side flanges 26 and 27. At a point radially outwardly from the ball bearing rotational axis of the arm, the metal of the arm is constrictingly bent to provide a tubular bearing 28.

A metal wheel carrier or arm extension 29 has a cylindrical shank 30 thereon in the tubular bearing 28 of the arm, and is rotatable therein as a bearing for the carrier 29, the carrier having a shoulder 31 by which inward movement of the shank 30 in the bearing is stopped and limited, the shoulder 31 rotatably abutting on the outer end of the tubular bearing 28. Outwardly beyond the head 29 of the wheel carrier it is provided with an arm 32 upon which is rotatably mounted a grooved wheel 33, the arm 32 at its outer end being bent over as at 34 in the form of a hook and overlapping the periphery of the grooved wheel 33.

The head 31 and shank 30 of the carrier or arm extension 29 have an internal bore 35 therein coaxially thereof and the arm 32 lies at one side of this bore.

A second grooved wheel 36 is provided between the side flanges 27 and 26 of the arm 19 and is mounted upon a shaft 37 having rotational bearing in the flanges 26 and 27; and the groove 38 in the wheel 36 is generally tangential to the axis of the conical head 16 of the bolt for a purpose to be described. As best shown in Fig. 4 but as indicated in the other figures, the shaft 37 is rotatable in elongated perforations or slots 39 and 40 in the respective side flanges 26 and 27 of the arm, the slots extending upwardly and at an inclination away from the axis of the bolt 17.

A spiral spring 41 has its inner end secured as by a rivet 42 to the pan bottom 1 and surrounds the cup form depression 10 and at its outer end

is secured as by a rivet 43 to the web 25 of the arm 19.

A two wire insulated electric cord 44 is led into the housing 5 through a perforation 45 in the pan bottom 1 and at the radially inner part of the reel groove 24 and is wound around and around in the reel groove, several convolutions being shown in section at 46, and from the reel, as at 47, it passes over the grooved wheel 33 and in the groove thereof, being trapped against displacement therefrom by the hook 34 on the end of the arm 32, and at 48 passes along the laterally displaced arm 32 and through the bore 35, and then over the grooved wheel 36 in the groove 38 thereof; the cord at this point being as shown in Fig. 1 closely adjacent as at 49 to the conical head 16 of the bolt 17. Beyond the wheel 36, the cord depends, preferably vertically, and is connected to the terminals of a lamp socket 50. The socket 50 projects upwardly into the housing through a perforation 51 in the cover plate 3, and externally of the cover plate the socket has a reflector 52 attached thereto and over-lapping the perforation 51, and a lamp 53 is inserted into the socket 50, and the socket has spring fingers 55 holding the reflector 52 thereon. An opalescent or light diffusing bowl 54 may if desired be mounted on the reflector 52 in any suitable manner and enclosing the lamp 53 between it and the reflector.

In the operation of the device, the helical spring 41 exerts resilient torque on the arm 19 in the direction to rotate it, for example in the clockwise direction as viewed from below in Fig. 1, and therefore tends to wind the cord upon the reel; and this causes the cord to be pulled in the direction of the arrow 56 and therefore holds the lamp 53 and reflector 52 upwardly against the cover plate 3; in the normal position illustrated in Fig. 1, wherein was referred to, the lamp normally functions as the dome light of a motor car.

To extend the cord to use the lamp as an extension cord lamp the user will grasp the reflector 52 and pull downwardly on it whereupon the portions of the cord within the housing and on the grooved wheels 36 and 33 will be put under tension and react upon the reel tangentially and this will cause the arm 19 to be rotated counterclockwise as viewed from below, and cause the cord to be unwound from the stationary reel groove 24, the cord passing downwardly and out of the housing through the perforation 51, and the rotation of the arm 19 will, as will be understood, wind up and put increased tension in the spiral spring 41.

When the operator releases his pull on the cord the spring 41 will turn the arm 19 in the other direction to wind the cord back on the reel.

Provision is made in the structure above described to permit the cord to be wound up on the reel as stated or optionally to grip the cord so that it will not wind up, whereby the operator does not have to keep tension in the cord to keep it extended, and this action will now be described.

So long as the operator by pulling on the cord maintains tension in it, the downward thrust of the cord on the grooved pulley 36 will hold the shaft 37 thereof in the lower end of the slots 39-40; and when he releases the tension on the cord but does not entirely remove it, the tension in the cord will keep the wheel 36 in that position during the winding up of the cord. However, if he abruptly releases all tension in the cord in those parts below the wheel 36, then the arm 19 will start and wind up the cord on the

wheel, and the cord running over the wheel 36 and rotating it will cause the shaft 37 to ride upwardly in the slots 39 and 40, and the inclination of these slots is such that the wheel 36 thus rising on the arm 19 will close up the clearance space 49 between the cord and the conical head 16 of the bolt, and wedge the cord between the wheel 36 and the conical head and grip it as shown in Fig. 4 and prevent further winding up of the cord, the conical head 16 acting as an abutment for this purpose. After the operator has finished with his uses of the lamp as an extension cord lamp, then by pulling upon the cord and putting tension therein the wheel 36 will be pulled back downwardly along the slot 39 and release the gripping action and then the arm will rotate and wind the cord up on the reel.

In order that the cord whether winding or unwinding from the reel will run freely in the groove of the grooved wheel 33, it is desirable that the cord will be tangential to the groove of the wheel 33 no matter by what configuration the cord winds on the reel, and it is for this reason that the wheel carrier 29 is arranged to swivel or have castering movement on the arm 9 by means of the bearing shank 30 in the tubular bearing 28. And to further facilitate this action, the pulley carrier arm 32 may as shown in Fig. 2 extend at an angle to the axis of the tubular bearing 28.

Outwardly of the housing 5, the two conductor cord 44 is opened and one conductor 57 reenters the housing through a perforation 58 and goes as at 59 to an off-and-on switch 60 mounted on the housing wall, and thence out of the housing again and as 61 to one side of the vehicle battery 62, the other side of which is grounded as at 63; and the other wire 64 goes to ground as at 65.

By means of the switch 60, the lamp 53 may be turned off and on, as will be understood.

The invention is not limited to the exact details of construction illustrated and described but is comprehensive of all changes and modifications which come within the scope of the appended claims.

I claim:

1. In an electric cord winding and unwinding mechanism, a frame; a reel stationarily supported on the frame; an arm extending generally radially of the reel and having a rotational bearing axis adjacent to and generally parallel to the central axis of the reel; an arm extension supported to oscillate on the arm on an oscillation axis extending longitudinally of the arm; a first grooved wheel rotatably supported on the arm extension to rotate on an axis at an angle to the said oscillation axis, and with a portion of the groove disposed adjacent to and outwardly of the reel periphery; a second grooved wheel rotatably supported on the arm with its groove generally tangential to the arm rotational axis; a spiral spring anchored at one end to the frame and at the other end to the arm for exerting torque on the arm to rotate it.

2. In an electric cord winding and unwinding mechanism, a frame; a reel stationarily supported on the frame; an arm extending generally radially of the reel and having a rotational bearing axis adjacent to and generally parallel to the central axis of the reel; a cord guide on the arm adjacent to and radially outward of the reel periphery; a grooved wheel guide having rotational bearing on the arm, and the groove of the wheel guide disposed generally tangential to the arm rotational axis; a conical abutment above the

groove of the wheel guide generally coaxial with the arm rotational axis and tapering toward the wheel groove and adjacent thereto; the bearing of the wheel guide comprising a shaft rotatable with the wheel guide and a trackway therefor, the trackway being at an angular inclination to the arm rotational axis and the shaft being rollable thereon to move the wheel guide groove toward the conical abutment; a spiral spring anchored at one end to the frame and at the other end to the arm for exerting torque on the arm to rotate it.

3. In an electric cord winding and unwinding mechanism, a frame; a reel stationarily supported on the frame; an arm extending generally radially of the reel and having a rotational bearing axis adjacent to and generally parallel to the central axis of the reel; an arm extension supported to oscillate on the arm on an oscillation axis extending longitudinally of the arm; a first grooved wheel rotatably supported on the arm extension to rotate on an axis at an angle to the said oscillation axis, and with a portion of the groove disposed adjacent to and outwardly of the reel periphery; a second grooved wheel rotatably supported on the arm with its groove generally tangential to the arm rotational axis; a spiral spring anchored at one end to the frame and at the other end to the arm for exerting torque on the arm to rotate it; and an electric cord extending through the grooves of the wheels and guided thereby and wound on the reel.

4. In an electric cord winding and unwinding mechanism, a frame; a reel stationarily supported on the frame; an arm extending generally radially of the reel and having a rotational bearing axis adjacent to and generally parallel to the central axis of the reel; a first grooved wheel rotatably supported on the arm with a portion of the groove adjacent to and radially outward of the reel periphery; a second grooved wheel having rotational bearing on the arm, the bearing comprising a shaft rotatable with the wheel and guide means for the shaft extending at an upward inclination away from the arm rotational axis, the groove of the second wheel disposed generally tangential to the arm rotational axis; a conical abutment above the groove of the second wheel generally coaxial with the arm rotational axis and tapering toward the wheel groove and adjacent thereto; a spiral spring anchored at one end to the frame and at the other end to the arm for exerting torque on the arm to rotate it; and an electric cord extending through the grooves of the wheels and guided thereby and wound on the reel.

5. In an electric winding and unwinding mechanism, a supporting frame; a stationary reel; an arm generally radial of the reel and supported to rotate on an axis adjacent to and generally parallel to the central axis of the reel; cord guide means on the arm; an electric cord running into the mechanism and over the guide means and wound on the reel; a spring reacting on the arm to rotate it in one direction; the guide means disposed to guide the cord to wind up on the reel upon spring-affected rotation of the arm; and the arm being rotatable in the reverse direction upon retracting pull on the cord from outside the mechanism to unwind the cord from the reel, and to tension the spring; the guide means comprising a wheel with a circumferential cord guiding groove therein generally tangential to the arm rotational axis; a bearing for the wheel comprising a shaft rotatable with the wheel, an upwardly

inclined guideway on the arm along which the shaft may roll, an abutment above the groove and adjacent thereto; pull on the cord from outside the mechanism holding the wheel shaft at a lower portion of the guideway and slack in the cord permitting the wheel to be rotated and propelled upwardly along the guideways, upon winding of the cord on the reel to wedgely grip the cord between the wheel and the abutment.

6. In an electric cord winding and unwinding mechanism, a supporting frame; a stationary reel; an arm generally radial of the reel and supported to rotate on an axis adjacent to and generally parallel to the central axis of the reel; cord guide means on the arm; an electric cord running into the mechanism and over the guide means and wound on the reel; a spring reacting on the arm to rotate it in one direction; the guide means disposed to guide the cord in alternate directions, and to guide it to be wound up on the reel upon spring effected rotation of the arm, upon the occurrence of slack in the cord; and to guide it to rotate the arm in the reverse direction and to be unwound from the reel, upon

the occurrence of tension in the cord from outside the mechanism, and to then tension the spring, a stationary abutment adjacent to the guided cord; the guide means comprising an element movable in alternate directions by tension in the cord and slack in the cord respectively; movement of the cord in the unwinding direction by tension in the cord moving the movable element away from the abutment and movement of the cord due to slack in the cord moving the movable element to wedge the cord between the movable element and the abutment to prevent winding of the cord on the reel.
